UNITED STATES PATENT OFFICE.

STANWOOD E. FLICHTNER, OF ENGLEWOOD, NEW JERSEY, ASSIGNOR TO COOPER HEWITT ELECTRIC COMPANY, OF NEW YORK, N. Y., A CORPORATION OF NEW YORK.

ADJUSTABLE SUPPORT FOR VAPOR-LAMPS.

No. 901,288.

Specification of Letters Patent.

Patented Oct. 13, 1908.

Original application filed July 28, 1904, Serial No. 218,473. Divided and this application filed January 9, 1905.
Serial No. 240,274.

To all whom it may concern:

Be it known that I, STANWOOD E. FLICHTNER, a citizen of the United States, and resident of Englewood, county of Bergen, State 5 of New Jersey, have invented certain new and useful Improvements in Adjustable Supports for Vapor-Lamps, of which the following is a specification.

The present invention relates to frames 10 for vapor electric lamps such as are represented by the well-known mercury vapor lamps now in common use.

The special object of the invention is to provide means whereby the starting of such 15 lamps may be readily accomplished either singly or in groups by means of tilting apparatus in which connection is first made between the negative and positive electrodes through a stream or column of mercury, and 20 afterwards such connection is broken by a proper manipulation of the apparatus, so that the current which originally flowed through the vapor column or stream shall 25 pass through the vapor path between the main positive and the main negative electrodes.

It has been found in practice that a variety of tilting frames is required for various purposes, whether for photographing by means 30 of mercury vapor lamps, or for printing, enlarging or copying, as the case may be.

This application is a division of my application filed July 28, 1904, Serial Number 218,473, and relates to a special application 35 of the invention therein described and shown.

In the drawings, Figures 1 and 2 are, respectively, front and side elevations of an apparatus especially adapted for printing; and Fig. 3 is a side elevation of a modified 40 form of apparatus for the same purpose.

Referring to Fig. 2, of the drawings, I have two lamps, 2, 2, mounted on frames, 1, 1, the two frames being themselves mounted upon standards, 3, 3. Behind the lamps are reflectors, 4, 4, adapted to throw the light forward upon blue printing paper (not shown) mounted upon a frame, 5, (see Fig. 1). The lamps are suitably pivoted and are mounted upon a carriage, 6, supporting the standards, 3, 3. 45 This carriage is shown as being adapted to travel under the frame 5 so that the printing frame may be exposed across its entire surface to the radiation of the lamps 2, 2. In 50

order to accomplish the starting of the apparatus by tipping or tilting, the carriage has to 55 be moved from under the frame 5, whereupon the tilting may take place through the medium of the frame 1 and its supporting rod, 7, which is pivoted in uprights 3, 3. The lamps having been started, the carriage can 60 be moved under the frame and the operation continued until a successful printing is accomplished.

Fig. 3 illustrates a similar apparatus, in which, however, the necessity for removing 65 the carriage as described above is avoided. In this construction, the frame 1 is pivoted at 8 in a standard, 9, and the operation of tilting the lamp or lamps for starting purposes is accomplished by releasing the upper 70 end of the frame 1 supporting the lamp or lamps 2 from the standard 3, and tilting it by hand until the lighting is accomplished after which the lamp or lamps can be restored to the position shown in the figure. The free 75 end of the frame 1 is supported upon a suitable shoulder on the standard 3, and may be released therefrom for the purpose of tilting the frame and the lamp or lamps 2, by hand for accomplishing the lighting as above set 80 forth.

In the construction shown in the drawing, it is possible to do away with the necessity of moving the lamps across the field of exposure, by providing suitable reflectors which will 85 diffuse the light over the said field.

I claim as my invention:

1. The combination with an inclined frame and a vapor electric lamp supported thereby, of a carriage supporting the frame 90 and means for tilting the frame upon its carriage for starting purposes.

2. The combination with an inclined frame, of a vapor electric lamp supported thereby, a carriage supporting the frame, the 95 lamp being pivoted to the frame near the bottom thereof and means whereby the lamp can be let down at the opposite end for starting purposes.

Signed at New York, in the county of New 100 York, and State of New York, this 3rd day of January A. D. 1905.

STANWOOD E. FLICHTNER.
